UNITED STATES PATENT OFFICE.

ELMER E. BUTCHER, OF INTERLAKEN, NEW JERSEY, ASSIGNOR TO MARCONI WIRELESS TELEGRAPH COMPANY OF AMERICA, A CORPORATION OF NEW JERSEY.

APPARATUS FOR RECEIVING ELECTRICAL OSCILLATIONS.

1,263,204.

Specification of Letters Patent. Patented Apr. 16, 1918.

Application filed May 14, 1914. Serial No. 838,418.

To all whom it may concern:

Be it known that I, ELMER E. BUTCHER, a citizen of the United States, and a resident of Interlaken, Monmouth county, New Jersey, have invented or discovered certain new and useful Improvements in Apparatus for Receiving Electrical Oscillations, of which the following is a specification.

The general object of my invention is to produce an apparatus suitable for the reception, detection and amplification of electrical oscillations.

My invention may be applied to the receiving of electrical oscillations, no matter how produced and irrespective of their general character. It may be used for receiving both continuous or damped oscillations and may be used in any connection in which it may be of service, as, for instance, in wireless or wire telegraphy, or wireless or wire telephony. I have shown in the drawing accompanying this specification a form which my invention may take. Since this drawing, however, shows only one of the many ways in which my invention may be applied, it is intended to be diagrammatic and illustrative only. The illustration chosen is in connection with wireless telegraphy, although, as I have pointed out, my invention is not confined to this use, and I do not wish to be limited to the specific form illustrated, since it will be apparent to those skilled in the art that many changes may be made without departing from the spirit of my invention.

One of the many advantages of my invention when used in connection with wireless telegraphy is that the resonant aerial circuit now used, which involves the erection of expensive aerials, masts, etc., and considerable difficulty of operation in tuning the aerial circuit to the received oscillations, may be dispensed with and a collector of energy out of resonance with the received oscillations used.

Referring to the drawing, I have shown at 1 a conductor which may be the wires of a telegraph or telephone line, a telephone line being preferably used if wires are employed as a conductor. These wires may be grounded as at 2 or not. Conductors 1 form a collector of energy merely and are not in resonance with the received oscillations, their purpose being merely to intercept them and transmit them to the detector,

It should be understood that wires 1, shown in the drawing, are illustrative of any elevated conductor, that they need not be telephone or telegraph wires nor, in fact, wires at all; nor need they be of any particular dimensions. 60

I have shown at 3 wires tapping the lines 1. In each of the wires 3 I preferably insert a condenser 4, although this condenser is not necessary. It is, however, desirable 65 in order to prevent interference with the other uses to which the line wires 1 may be put, either by reason of the connection of several of these wires 1 to each other, or by reason of the operation of the oscillation 70 detecting apparatus. Wires 3 are connected together as at 5, at which point a local detector circuit is connected, comprising a coil 6, a variable condenser 7, and a detector 8. Coil 6 is preferably in the form of a long 75 coil having a large inductance and a relatively low distributed capacity and acts as a linear oscillator, producing a point of maximum potential to which the detector is connected. Condenser 7 is a small variable condenser and is not essential to the operation 80 of my device, although I prefer to use it. Coil 6 is preferably a coil having a relatively large number of turns and a natural period approximating that of the received oscillations, and condenser 7 is preferably of relatively small capacity. 85

The specific form of detector I have illustrated is a multiple element valve detector of the ordinary type, although it will be understood that any other suitable form of detector may be used. Detector 8 consists of a sealed vessel inclosing three electrodes, a grid electrode 9 by which it is connected to the detecting circuit; a plate electrode 10; 90 and a filament electrode 11. The filament electrode 11 is heated by means of a battery or other source of heat 12, and is connected, through a battery 13 and a telephone 14, to plate electrode 10. 95

In the operation of my device connection is made to any convenient and suitable conductors 1, which are not tuned to the periodicity of the received oscillations. However, the circuit including the coil 6 and condenser 7, but omitting condensers 4 is tuned 100 to the received oscillations by varying the constants in the usual manner. The batteries 12 and 13 are adjusted to give a maximum response in the telephone 14. 105 110

When arranged and operated as I have described it signals may be received and detected without in any way interfering with the ordinary uses of the conductors to which 5 the detector has been attached.

What I claim is:

1. In an apparatus for receiving electrical oscillations, a collector, an open local circuit including a detector, and a condenser between said collector and said local circuit. 10
2. In an apparatus for receiving electrical oscillations a collector of energy out of resonance with the received oscillations and an open local detector circuit tuned to the 15 periodicity of the received oscillations and comprising a detector, an inductance and a capacity in series.
3. In an apparatus for receiving electrical oscillations a collector of energy out of resonance with the received oscillations, a local 20 detector circuit associated therewith, said circuit being tuned to the periodicity of the received oscillations and containing an inductance consisting of a coil having a nat-

ural period approximating that of the received oscillations, a capacity and a detector in series and a capacity intervening between the collector of energy and the local detector circuit. 25

4. In an apparatus for receiving electrical 30 oscillations, a grounded collector, an open local circuit including a detector, and a condenser connected between said collector and said local circuit.

5. In an apparatus for receiving electrical 35 oscillations, a collector, an open local circuit including a detector, said local circuit including a capacity and inductance, said detector, capacity and inductance being connected in series, and a condenser between 40 said collector and said local circuit.

In witness whereof I have hereunto signed my name in the presence of two witnesses this 13th day of May, 1914.

ELMER E. BUTCHER.
